DESIGN FOR A NURSERY BIB

Jean E. Vivaudou, New York, N. Y.

Application May 12, 1948, Serial No. 146,331

Term of patent 3½ years

(Cl. D3—26)

To all whom it may concern:

Be it known that I, Jean E. Vivaudou, a citizen of the United States, residing at New York, in the county of New York and State of New York, have invented a new, original, and ornamental Design for a Nursery Bib, of which the following is a specification, reference being had to the accompanying drawing, forming a part thereof.

In the drawing:

Fig. 1 is a front elevational view of a nursery bib, showing my new design;

Fig. 2 is a rear elevational view of the same, showing it on a reduced scale; and

Fig. 3 is an enlarged sectional view taken on the line 3—3 of Fig. 2.

I claim:

The ornamental design for a nursery bib, as shown.

JEAN E. VIVAUDOU.
